SOLVENT REFINING HYDROCARBON OIL

Bernard Y. McCarty and Howard H. Gross, Beacon, N. Y., assignors to The Texas Company, New York, N. Y., a corporation of Delaware

Application November 5, 1936, Serial No. 109,234

3 Claims. (Cl. 196—13)

This invention relates to solvent refining hydrocarbon oil, and more particularly solvent refining of mineral lubricating oil.

The invention contemplates a process of solvent refining in which the oil is subjected to a primary extraction with a selective solvent to form extract and raffinate phases. The more paraffinic constituents of the extract phase, formed in the primary extraction, are removed and separately subjected to re-extraction with a selective solvent. The process involves salting-out or separating these more paraffinic constituents of the primary extract phase by treating the primary extract phase with heavy extract phase material from which the solvent has been removed, all or in part, and from which the relatively paraffinic constituents have been removed.

More specifically, the invention contemplates effecting primary extraction with a solvent, such as furfural, to produce a raffinate phase containing high viscosity index constituents, and an extract phase comprising low viscosity index constituents and constituents of intermediate as well as relatively high viscosity index dissolved in the bulk of the solvent.

The extract phase is then treated so as to separate therefrom a fraction comprising constituents of the oil of intermediate and relatively high viscosity index, and which will be referred to as intermediate oil. This intermediate oil is separated from the extract phase by mixing with the extract phase a suitable proportion of extract material, accumulating in the subsequent steps of the process, from which the intermediate oil has been removed and from which the solvent has also been removed, all or in part.

We have found that the addition of this heavy extract material, from which the solvent and intermediate oil has been removed, to the extract phase produced in the primary extraction exerts a salting-out effect such that the intermediate oil is separated from the extract phase to a very high degree. The separation of the intermediate oil so obtained is more efficient, and a higher yield is obtained than when the extract phase is subjected merely to cooling and settling.

The intermediate oil so obtained is then extracted with fresh solvent, and in a zone separate and apart from that in which the fresh charge is being extracted.

We have found that it is advantageous to subject the intermediate oil to a separate extraction with fresh solvent. By doing so, it is possible to obtain a greater yield of valuable lubricating oil products from the initial charge stock than is

realized where the intermediate oil is returned to the primary extraction zone and re-extracted in the presence of the fresh charge.

While furfural has been mentioned, it is contemplated that other solvent compounds, having selective action as between constituents of the oil of differing viscosity indices, may be employed. For example, other solvents may comprise aniline, benzaldehyde, nitrobenzene, etc. The selective solvent may be used alone, or in the presence of a suitable modifying solvent. Among the modifying solvents which may be used are benzol or one of its homologs; light petroleum hydrocarbons such as propane, butane, natural gasoline or its constituents; and naphtha. Low-boiling aliphatic ethers may be used, such as ethyl and isopropyl ether.

In order to more fully describe the invention, reference will now be made to the accompanying drawing.

As shown in the drawing, the oil to be treated is introduced to the lower portion of an extraction tower 1, while the selective solvent is introduced to the upper portion of the tower. Where the selective solvent is lighter than the oil undergoing treatment, it is, of course, contemplated that the points of entry of the solvent and oil will be reversed.

The solvent and oil flow countercurrently in direct contact with each other through the tower. Contact between the two bodies is facilitated by providing suitable contacting surfaces within the tower.

The raffinate phase comprising high viscosity index oil of around 100 viscosity index accumulates in the top of the tower and is removed therefrom as a primary raffinate phase. The solvent is removed from this phase by distillation, and the remaining oil subjected to such further treatment as may be desired.

The extract phase accumulating in the bottom of the tower is removed as a primary extract phase and conducted through a mixing coil 2 to a settler 3. In the mixing coil, the extract phase is mixed with heavy extract material accumulating in a subsequent step of the process, as will be explained below. This heavy extract material is introduced to the mixer from a pipe 4. It may be mixed with the extract phase in the proportion of from one to five parts of extract material to twenty parts of primary extract phase.

The mixture is allowed to stand in the settler 3, either with or without cooling. Where cooling is desired, it may be accomplished by submerging

the mixer coil 2 within a body of refrigerant liquid.

As a result of such settling, the more paraffinic constituents of the primary extract phase separate as an intermediate oil, leaving as a bottom layer the heavier extract material comprising constituents of low viscosity index dissolved in the solvent.

The intermediate oil is removed and conducted 10 to the lower portion of a secondary extraction tower 5 wherein it is brought into countercurrent contact with fresh solvent introduced to the upper portion of the tower. The raffinate phase accumulating in the top of the tower is removed 15 therefrom as a secondary raffinate phase.

By adjusting the conditions of temperature and solvent dosage, this secondary raffinate oil, after removal of the solvent, may be such as to have practically the same viscosity index as the primary raffinate where the primary raffinate ranges 20 from 75 to 85 in viscosity index. Where the primary raffinate oil ranges from 85 to 100 in viscosity index, this secondary raffinate oil will be from about two to ten points below the primary raffinate oil in viscosity index.

The extract phase accumulating in the lower portion of the secondary tower is removed therefrom as a secondary extract phase and is conducted to a stripper 6 wherein the solvent is removed by distillation, preferably in the presence 30 of steam.

Referring again to the settler 3, the layer of extract material and solvent accumulating in the bottom thereof is withdrawn to a stripper 7 35 wherein the solvent is also removed by distillation, all or in part. The residue accumulating in the bottom of the stripper 7, and known as primary extract, is withdrawn, and the required proportion thereof returned through the pipe 4 40 to the mixer 2.

If desired, the material accumulating in the bottom of the stripper 6, and referred to as a secondary extract, may be returned in part through the pipe 4 to the mixer 2. It is contemplated that either primary extract or secondary extract, or a mixture of the two, may be returned to the mixer 2 for addition to the primary extract phase.

In some instances, it is contemplated that it 50 may be advantageous merely to strip a suitable proportion of the solvent from the primary extract phase, and then subject the remaining mixture to settling in order to separate the intermediate oil therefrom. This may be resorted to, 55 for example, where the ratio of solvent to oil in the primary extraction has been relatively large. In that case, the primary extract phase is conducted directly to a still 8 wherein the desired amount of solvent liquid is removed therefrom. The remaining extract phase material is then withdrawn from the still and conducted to the settler 3 wherein it may be subjected to settling, either with or without cooling. Where cooling is desired, it may be imparted by circulating a cooling medium through a coil 9 provided within the settler 3 as shown.

The removal of the solvent causes a concentration of oil in the extract phase so that the relatively insoluble and more paraffinic constituents 70 will more readily separate from the mixture upon settling.

The residue from the still 8 may also be introduced to the mixer 2 and there mixed with heavy extract material prior to introduction to the 75 settler 3.

In carrying out the foregoing operation, where furfural is used as the selective solvent, the temperatures in the primary extraction tower may range from 220° to 280° F. while the temperatures in the secondary extraction tower may be the same or range from around 190° to 250° F. It is advantageous to maintain a temperature differential through the tower between the points of solvent and oil introduction, the top of the tower being at the higher temperature.

The solvent may be introduced to the primary tower in the proportion of around two to eight parts of solvent to one part of oil, while in the secondary tower it may be used in the proportion of around one to four parts of solvent to one part of intermediate oil. It is contemplated, however, that, in some instances, depending upon the nature of the stock, it may be advantageous to use similar temperatures and similar solvent proportions in both towers. On the other hand, it may be desirable to employ higher temperatures or higher solvent dosages, or both, in the secondary extraction tower.

We have carried out a number of tests showing the amount of intermediate oil separated by treating a primary extract phase with different amounts of heavy extract material. The extract phase in question was obtained by extracting (corresponding to the above described primary extraction) a distillate lubricating oil stock derived from Mid-Continent crude, having a gravity of 23.4 and a Saybolt Universal viscosity at 210° F. of 102 seconds. This stock was extracted with furfural in a countercurrent tower with a temperature at the top of 264° F. and at the bottom 30 of 204° F., using five parts of furfural to one part of oil.

The resulting primary extract phase comprised about 10% oil and 90% solvent by volume. A sample of this extract phase, with the solvent removed, had an A. P. I. gravity of 13.3 and a Saybolt Universal viscosity of 224.5 seconds at 210° F.

It was found that:

A. When 200 cc. of this extract phase, containing 10% oil and 90% furfural, was cooled from 200° F. to 130° F., the amount of intermediate oil separating was 10 cc.

B. 200 cc. of the original extract phase referred to in A was then mixed with 100 cc. of extract phase from which the 10 cc. intermediate oil had been removed but which still contained the solvent. When this mixture was cooled from 200° F. to 130° F., the intermediate oil which separated amounted to 14 cc.

C. 200 cc. of the original extract phase referred to in A was mixed with 100 cc. of extract material from which, in addition to the removal of the intermediate oil, about 40% of the solvent had been stripped. When cooling this mixture from 200° F. to 130° F., the amount of intermediate oil which separated was 35 cc.

D. On the other hand, when 200 cc. of the original extract phase referred to in A was mixed with 10 cc. of extract material, from which both the intermediate oil and all of the solvent had been removed, there was a separation upon cooling, through the same temperature range, of only 20 cc. of oil.

These examples show that by mixing the primary extract phase with extract phase from which the intermediate oil has been previously removed, and cooling the mixture from 200° F. down to 130° F., much more intermediate oil is separated than when the original primary extract 75

phase is cooled in the absence of the heavy extract material. The data also show that the maximum yield of intermediate oil separated is obtained by employing as the salting-out agent extract phase material from which about half of the solvent has been stripped in addition to the removal of the intermediate oil.

Obviously, many modifications and variations of the invention, as hereinbefore set forth, may be made without departing from the spirit and scope thereof, and therefore only such limitations should be imposed as are indicated in the appended claims.

We claim:

1. In the refining of hydrocarbon oil by solvent extraction to separate the oil into fractions of different viscosity index, the method which comprises extracting the oil with a selective solvent in a primary extraction zone, forming a primary raffinate phase containing oil of high viscosity index and a primary extract phase containing oil of intermediate and low viscosity index, separately withdrawing said phases from the primary extraction zone, incorporating in the withdrawn primary extract phase a precipitant consisting of a separate portion of primary extract phase from which has been removed such oil as separates upon settling the primary extract phase at a temperature substantially below that at which the primary extract phase was formed and from which about half of the solvent has been removed, subjecting the withdrawn primary extract phase containing the incorporated precipitant to settling, thereby forming an oil phase comprising oil of intermediate viscosity index and a heavy extract phase comprising oil of low viscosity index, and separating said phases.

2. In the refining of hydrocarbon oil by solvent extraction to separate the oil into fractions of different viscosity index, the method which comprises extracting the oil with a selective solvent in a primary extraction zone, forming a primary

raffinate phase containing oil of high viscosity index and a primary extract phase containing oil of intermediate and low viscosity index, separately withdrawing said phases from the primary extraction zone, incorporating in the withdrawn primary extract phase a precipitant consisting of a separate portion of primary extract phase from which has been removed such oil as separates upon settling the primary extract phase at a temperature about 70° F. below the temperature at which the primary extract phase was formed and from which about half of the solvent has been removed, subjecting the withdrawn primary extract phase containing the incorporated precipitant to settling, thereby forming an oil phase comprising oil of intermediate viscosity index and a heavy extract phase comprising oil of low viscosity index, and separating said phases.

3. In the refining of mineral lubricating oil by extraction with furfural, the method which comprises extracting the oil with furfural in a primary extraction zone at a temperature of around 200° F. and above, forming a primary raffinate phase containing high viscosity index oil and a primary extract phase comprising low and intermediate viscosity index oil dissolved in the bulk of the solvent, separately withdrawing said primary phase, incorporating in the primary extract phase a precipitant consisting of a separate portion of primary extract phase from which has been removed substantially all of the oil that separates upon settling the primary extract phase at a temperature of about 130° F. and from which about half of the solvent has been removed, subjecting the withdrawn primary extract phase containing the incorporated precipitant to settling, thereby forming an oil phase comprising oil of intermediate viscosity index and a heavy extract phase comprising oil of low viscosity index, and separating said phases.
